UNITED STATES PATENT OFFICE.

MAX KORCHMAR, OF CINCINNATI, OHIO.

BRIEF OR SIMILAR CASE.

Application filed July 20, 1926. Serial No. 123,770.

This invention relates to improvements in brief cases and the like and has for its object the provision of a device of this kind, which is especially adapted for use by salesmen, professional men and others who may frequently find it advisable in use to carry paper and other articles relating to two disconnected matters and who may desire to have a separate access to any papers without disclosure to others present, any papers or other articles pertaining to another matter and other objects.

Another object is to provide a carrying case of the class described which is supported immediately beneath the handle member thereof, and which always retains a state of nice balance regardless of irregularity of disposed articles therein.

Another object is to provide a case of this kind wherein a single pair of tying straps serves to accommodate both compartments of the case.

These and other objects are attained by the means described herein and disclosed in the accompanying drawings in which:

Fig. 1 is a view of one side of the case of my invention.

Fig. 2 is a cross sectional view taken on line 2—2 of Fig. 1.

Fig. 3 is a fragmental perspective view of a hinged and supported member forming a part of my invention as shown partly in closed section.

Devices of the class herein referred to are usually made of leather or similar material and ordinarily comprise a combined rear wall and flap, which flap is usually secured by a suitable locking means or clasp to a front wall, the handle member is normally secured to the flap and as a result thereof, if the flap is not secured, the case will depend at an angle to the vertical.

In the present device I employ a central partition wall 7 to which is secured an expandable bottom member 8 and an elongated U-shaped hinge member which comprises side walls 9 and 10, between which the top edge of the center wall 7 is secured. The hinge member may be of metal and the center partition 7 may be secured thereto by any suitable means such as rivets 11 extending through aligned perforations 12 and through the partition 7. A flat strip 13 carries a plurality of depending loops 14 which may be conveniently formed by striking them from the body of strip 13. The loops 14

seat in notches 15 cut at intervals from the rounded top edge 16 of the lower hinge member. Rod 17 serves as pintle and hingedly secures the plate 13 and lower hinge member 18 together. The hinge plate 13 has a plurality of perforations 19 there through for receiving rivets 20 which serve to secure hinge plate 13 centrally along a generally rectangular piece of material which forms two separately openable flaps 21 and 22. A handle 23 is secured by any suitable means such as the customary pair of rings 24 to the rectangular member 25 comprising flaps 21 and 22. Side walls 26 and 27 are secured along their bottom edges to the telescoping bottom wall 8. The flap 21 and side wall 26 carry complementary locking means of any approved type such as plate 28 carrying a hook or the like which is received by locking mechanism 29. The flap 22 and side wall 27 also carry complementary snap lock members 30 and 31. Top tying straps 32 extend across the top of rectangular member 25 and through suitable loops 33 carried by flaps 21 and 22 thereof.

Lower tying straps 34 extend across the bottom of the device and are retained or positioned upon side walls 26 and 27 by loops 35. Each end of the bottom tying straps 34 carries a suitable buckle 36 which receives an end of the top tying strap 32. Flexible end walls 37 of telescoping or of a bellows form are secured at opposite ends to the telescoping bottom wall 8 and to side walls 26 and 27. A partition 38 may be extended between end walls 37 and bottom wall 8, for providing a pair of separate compartments on one side of the center wall 8, while a similar partition may be employed on the other side of the center wall 7 if desired. As shown herein, however, a sheet of material 39 sewed or otherwise secured at its bottom and sides to the center wall 7 provides a pocket and a large opening compartment on the remaining side of the center wall.

The hinge member 13 may be concealed and also additionally secured to the inside of the rectangular member 25 by inserting a strip of suitable finish material such as leather between the hinge members, said material being slotted to receive the loops 14 and 16 of the hinge members.

From the foregoing it will be apparent that there has been provided a simple, nicely balanced case comprising two divisions each of which is closed by a separate flap and lock

and both divisions are adapted to be additionally supported by a single pair of tying straps.

It will be readily evident that a salesman for example who carries two different lines of goods may dispose the samples of one line in one division and those of the other in the remaining division and that he may keep one or the other of the flaps closed and locked so that those articles or papers which he does not care to disclose may be safely concealed from view in the case. It will of course be understood that the utility of the device is not confined to its use by salesmen. It will be found that personal effects may be readily disposed in one of the compartments when a person is making a trip and does not wish to embarrass himself with separate baggage but who nevertheless does not desire to have his business papers or the like confused with personal effects.

While I have disclosed the one embodiment of my invention I do not desire to be eliminated to the exact disclosure since it will be readily apparent to those skilled in the art, that the structure may be modified within the spirit and scope of this invention.

What I claim is:

1. In a carrying case the combination of a center wall, side walls disposed on each side of the center wall, a bottom wall connecting the side and center walls, a member hingedly mounted intermediate its longitudinal edges upon the top edge of the center wall and providing downwardly foldable flaps on each side of the center wall, separable locking means for securing each flap to a side wall and a handle member secured in alignment with the top of the center wall.

2. In a device of the class described the combination of a pair of spaced side walls, an intermediate wall disposed between said side walls and extended above them, a transverse member hingedly mounted to the intermediate wall, a handle member carried by the transverse member at its hinged mounting, bottom and end closures secured to the side walls along three sides thereof whereby to provide a pair of compartments each of which is open at its top and closed by a different section of the hingedly mounted transverse member and means for closing each of said compartments.

3. In a device of the class described the combination of a center wall, a hinge member secured along the top edge of said center wall, a transverse plate hingedly mounted to said hinge member, a cover member secured to the plate, means comprising side, bottom and end walls for providing a compartment on each side of the center wall, said compartments having openings at their tops, adapted to be closed by portions of the cover member and means of securing said portions of the cover member to the side walls.

4. In a device of the class described the combination of a handle member, a center wall hingedly mounted below the handle, a transverse flexible member interposed between the handle and the top of the center wall and compartments comprising side walls, bottom walls, and end walls disposed on each side of the center wall and independently closable by separate portions of the transverse member.

5. In combination a carrying case having a central partition providing a pair of compartments therein, a flexible member hingedly secured intermediate its side edges to the top of the partition and foldable for closing the compartments, and a two part tying strap, one part of which is carried by the flexible member and one by the case, one end of each strap member being adapted to be secured to an end of the remaining strap member on each side of the case whereby the foldable member may be retained in a closed position over each compartment.

6. In combination a carrying case having a fixed central partition, expansible bottom and end walls secured to the partition, a side wall on each side of the central partition providing expansible compartments, a flexible member secured to the partition forming a closure for said compartments, a pair of strap members slidably mounted transversely of the flexible member, a second pair of strap members extending about the bottom and terminating at opposite sides and means for attaching the free ends of the straps together at each side of the case and adapted to accommodate varied degrees of expansion of the compartments.

7. In combination with a carrying case comprising a top closure member and separate compartments closable separately by oppositely sides of a top closure member, of two part straps comprising strap portions slidably retained in transverse relation with the closure member and other strap portions slidably retained about the bottom and sides of the case and means comprising a pair of fastening members for each pair of straps whereby the straps may be adjustably secured together at each side of the case.

8. In a brief case the combination of a flexible member, a central wall hingedly suspended from one face of the flexible member intermediate the longitudinal edges thereof, a handle secured to the opposite face of the flexible member immediately above the hinge mounting, pocket structures on opposite sides of the central wall and closable by portions of the flexible member and means for retaining the said portions of the flexible member in closed position.

In testimony whereof, I have hereunto subscribed my name this 17th day of July, 1926.

MAX KORCHMAR.
